The patent or application file contains at least one drawing executed in color. Copies of this patent or patent application publication with color drawing(s) will be provided by the Office upon request and payment of the necessary fee.

A portion of the disclosure of this patent contains material to which a claim for copyright is made. The copyright owner has no objection to reproduction of the patent document as it appears in the Patent Office, but reserves all other rights. The sole FIGURE is a front view of a display screen with graphical user interface for display on a computer screen, electronic device screen, etc., or a portion thereof, showing the new design in color.

The broken line around the design indicates a display screen or portion thereof, and is not part of the claimed design. The broken lines depict portions of the article and form no part of the claimed design.
